Patented Apr. 1, 1919.

UNITED STATES PATENT OFFICE.

HERMAN M. OPIZZ, OF NORWICH, CONNECTICUT.

ADJUSTABLE WINDOW-SCREEN.

1,299,016.

Specification of Letters Patent.

Patented Apr. 1, 1919.

Application filed March 11, 1918. Serial No. 221,781.

To all whom it may concern:

Be it known that I, HERMAN M. OPIZZ, a citizen of the United States, residing at Norwich, in the county of New London, State of Connecticut, have invented certain new and useful Improvements in Adjustable Window-Screens; and I do hereby declare the following to be a full, clear, and exact description of the invention, such as will enable others skilled in the art to which it appertains to make and use the same.

This invention relates to improvements in window screens and particularly to adjustable window screens.

One object of the present invention is to provide a novel and improved construction of a window screen wherein the frame is slidably adjustable to fit window frame openings of different widths and whereby the usual opening between the two sliding sections will be completely covered by the screen cloth.

Another object is to provide a novel and improved structure wherein the screen frame is formed from a minimum number of parts and wherein the screen cloth is automatic in its operation to cover the screen frame when said frame is adjusted to larger or smaller windows.

Other objects and advantages will be apparent from the following description when taken in connection with the accompanying drawing.

In the drawing:

Figure 1 is an elevation of a window screen made in accordance with my invention.

Fig. 2 is a horizontal longitudinal sectional view taken on the line 2—2 of Fig. 1.

Fig. 3 is a vertical transverse sectional view taken on the line 3—3 of Fig. 1.

Fig. 4 is a vertical longitudinal central sectional view through one corner of the frame showing the roller support and the sliding connections between the sections of the frame.

Fig. 5 is a plan view of the blank from which the section 11 of the frame is formed.

Fig. 6 is a plan view of the blank from which the section 10 of the frame is formed.

Referring particularly to the accompanying drawing 10 and 11 represent, respectively the two sections of the screen frame. The section 10 is formed from a single metal blank and includes the vertical end member 12 and the parallel arms 13 which extend from the ends of said member 12. It will be

noted that the end member 12 and the arms 13 are hollow and are rectangular in cross section the wall of each portion which is directed toward the interior of the frame being formed with a longitudinally extending slot 14. In the outer wall of each of the arms 13 there is formed a longitudinal slot 15, the purpose of which will appear hereinafter. Extending from the side walls of the slot of the end member 12, and in the direction of the center of the frame, are the lips or flanges 16 between which is secured the adjacent end of the strip of screen fabric 17.

The other section 11, of the frame includes the hollow end member 18 and the hollow parallel arms 19 which extend from the ends of said end member. The end member and arms are preferably rectangular in cross section and of slightly greater area than the arms of the section 10, whereby said arms of the section 10 are disposed slidably within the arms of the section 11. The inner walls of the arms 19 are formed with slots 20 which align with the slots of the arms 13 to receive slidably therein the longer marginal edges of the screen cloth. The outer wall of each of the arms 19 has formed thereon a struck-in lug 21 which is disposed for slidable engagement in the slot 15 whereby the arms of the two sections are held in proper relation and limited in their longitudinal slidable movements. The inner wall of the end member 18 is formed with a slot 22, which connects, at its ends, with the slots of the arms 19. Struck inwardly from the upper and lower end portions of the outer wall of the end member 18 are the apertured lugs 23, and disposed longitudinally within this end member 18 is a roller 24, the pintles 25 of which are engaged through the apertures of the lugs 23. The remaining end of the strip of screen cloth is secured to and arranged to be wound on this roller.

The roller is preferably of the spring shade roller type, whereby when the sections of the screen frame are pulled apart the roller will permit the screen to unwind, and when the sections are pushed together, the roller will wind up the excess of the screen cloth, thereby filling up the entire opening in the screen frame with a continuous sheet or strip of screen cloth, and thus obviating the usual crack or opening between the sections of the ordinary screen frame wherein each section carries a separate piece of screen cloth.

It will be noted that the inturned flanges of the end member 12 are formed with teeth 26 which firmly grip the end of the screen fabric and hold the same within the slot of 5 the end member.

Attention is called to Fig. 5, which shows the blank from which the section 10 is formed. It will be noted that at two points, 10 27, on each of the longer marginal edges of the blank, there are formed the right-angular notches the walls of which meet to form the lines or joints 28, when the section is properly folded into the condition shown in Fig. 1.

15 The blank, Fig. 6, of the section 11, is similarly formed with the notches 29 which form the joints 30 of the completed section, as seen, also, in Fig. 1. Thus the frame is formed from two pieces of metal.

20 If desired the flanges of the slot of the end member 18 may be rolled outwardly, as seen at 31, whereby the sliding of the screen cloth through the slot is greatly facilitated.

What is claimed is:

25 1. A blank for a window screen section including an elongated strip of metal hav-

ing longitudinal parallel fold lines, the opposite sides of the strip being formed with right angular notches which divide the strip into end and intermediate sections, the end sections being formed with longitudinal slots and the intermediate section being formed with serrations on its opposite longer edges, fold lines connecting the angles of the notches. 30

2. A blank for a window screen section including an elongated strip having longitudinal parallel fold lines, the opposite longer sides of the strip having opposite disposed right angular notches which divide the strip into three sections, the intermediate section having struck up lugs adjacent its ends, the end sections each having a struck up lug adjacent its outer end, the strip having transverse fold lines connecting 45 the inner angles of the notches.

In testimony whereof, I affix my signature, in the presence of two witnesses.

HERMAN M. OPITZ.
